PRESSURE VACUUM RELIEF RADIATOR CAP

Filed July 19, 1948

UNITED STATES PATENT OFFICE

2,582,209

PRESSURE VACUUM RELIEF RADIATOR CAP

Lowell J. Smith and Dawson Friend, Connersville, Ind., assignors to Stant Manufacturing Company, Connersville, Ind., a corporation of Indiana

Application July 19, 1948, Serial No. 39,518

4 Claims. (Cl. 220—44)

1

The present invention relates to a cap for automobile radiators or similar containers, incorporating valve means of such character as automatically to relieve either positive or negative excessive pressure differentials between the interior of the container and the atmosphere. The primary object of the invention is to simplify the construction of such closures; but further objects are to render the structure less expensive to manufacture, and less subject to damage, breakage, or wear. A further object of the invention is to provide, in such an organization, an improved, and less expensive, form of guide mounting for a reciprocatory and rotatable valve assembly. A still further object of the invention is to provide an assembly of the character under consideration, so constructed that there will be substantially no scrubbing or scuffing wear between the parts of the closure assembly and the cooperating parts of the mouth of the container to be closed. Further objects of the invention will appear as the description proceeds.

To the accomplishment of the above and related objects, my invention may be embodied in the form illustrated in the accompanying drawings, attention being called to the fact, however, that the drawings are illustrative only, and that change may be made in the specific construction illustrated and described, so long as the scope of the appended claims is not violated.

Fig. 1 is a broken vertical section through a cap constructed in accordance with the present invention, assembled with a standard form of automobile radiator filler spout;

Fig. 2 is a vertical section through our improved cap; and

Fig. 3 is a transverse section through the assembly of Fig. 2 taken substantially on the line 3—3 thereof.

Referring more particularly to the drawings, it will be seen that we have illustrated, more or less diagrammatically, a standard form of automobile radiator filler spout 10, formed to provide a valve seat 11, and formed, at its upper end, with a perimetral seat 12 defined by an outwardly and downwardly turned flange 13. In accordance with standard practice, we have shown an overflow pipe 14 communicating with the interior of the spout 10 between the seats 11 and 12.

A cap member 15 may preferably be punched and shaped from sheet metal, and is formed to provide a perimetral skirt 16 which, at spaced points, carries inturned fingers 17 for cooperation with the cammed lower edge of the flange 13, in accordance with standard practice. Pref-

erably, the central portion of the cap member will be distorted inwardly, as at 18, to provide a central, axially inwardly projecting, substantially cylindrical boss 19. Loosely journalled on the boss 19 is a flexible diaphragm 20, preferably formed of thin, resilient metal, and adapted to cooperate with the seating surface 12 to seal the upper end of the spout. The parts are so proportioned and designed that, when the cap member 15 has been turned to locked position, the sealing element 20 will have been flexed upwardly adjacent its periphery.

The distorted portion 18 of the cap member 15 is provided with a perforation 21, and an elongated, hollow, preferably cylindrical member 22 is formed at its upper end with an inturned flange 23 defining an opening substantially identical in dimension with the opening 21. A rivet 24 is received in those openings and headed over 20 against the outer surface of the cap member and the inner surface of the flange 23 to secure the member 22 fixedly and rigidly to the cap member. At its lower end, the elongated member 22 is formed with an outturned flange 25.

A spring seat or ring 26 is formed to provide axially spaced portions 27 and 28, substantially parallel with each other and perpendicular to the axis of the element 22, said portions 27 and 28 being joined by an integral, axially extending 30 wall. The outer perimeter of the portion 28 is turned upwardly to provide a cylindrical flange 29. The flange 27 is proportioned and designed to have a sloppy, axially slid able and rotational fit upon the elongated member 22, but to engage the flange 25 of said member to limit movement of said spring seat in a direction away from the cap member 15. It will be apparent that, because of this sloppy fit, the spring seat 26 may rock relative to the axis of the member 22, and also may freely rotate and reciprocate relative to said member.

A coiled spring 30 surrounds the member 22 and is confined between the spring seat 28 and the sealing member 20, thereby pressing said sealing member 20 frictionally against the inner surface of the cap member 15. It will be seen that the spring 30 comprises the sole means for holding the sealing member 20 in place upon the boss 19 and against the inner surface of the cap member 15.

A valve assembly is indicated generally by the reference numeral 31. It comprises an annular disc 32 having an internal peripheral flange 33 turned axially in one direction out of the general plane of the disc, and an external peripheral

flange 34 turned in the opposite direction out of said plane. The flange 34 is so proportioned and designed as snugly to receive the flange 29 of the ring 26; and, after assembly of said disc upon said ring, the upper edge of the flange 34, which flange has a longer axial extent than does the flange 29, may be crimped over the flange 29, throughout its periphery, or at a plurality of spaced points 35 about its periphery.

An annular gasket 36 is sleeved on the flange 33 of the disc 32 and pressed into engagement with that surface of said disc remote from the ring 26. The gasket 36 may be held in place on the disc 32 in any suitable fashion; but we prefer to secure it in place by means of a thimble rivet 37 having an upper flange 38 spun or peened into engagement with the upper surface of the disc 32 and a lower flange 39 spun or peened into engagement with the exposed surface of the gasket 36.

A valve 40 is arranged to cover the opening through the rivet 37 and to bear against the exposed surface of the gasket 36 upon a circular line lying beyond the limits of the flange 39. Said valve 40 is carried upon a stem 41 which passes freely through the rivet 37 and is provided, at its upper end, with a suitable abutment such as a head 42. A coiled spring 43 is confined between said head and the flange 38 of the rivet 37, resiliently holding the valve 40 in sealing engagement with the gasket 36.

It will be seen that, when the cap is brought into operative association with the spout 10, the gasket 36 will come into sealing engagement with the valve seat 11. As the cap is rotated to move the fingers 44 over the camming surfaces of the flange 43, the member 22 rotates freely with respect to the ring 26 and the valve assembly 31, and moves axially downwardly relative to said ring and valve assembly. Thus, the gasket 36 is not caused to scrub against the seat 11. Likewise, the sealing member 20 is brought into engagement with the seating surface 12 before the cap member 15 reaches its locked position. Because said sealing member is held only frictionally against the inner surface of the cap member 15, the cap may rotate relative to said sealing member, also, during the latter portion of the locking movement of said cap member. It will be seen that, because of the sloppy fit between the ring 26 and the member 22, the gasket 36 will engage securely upon its seat 11 in spite of any minor misalignment between the member 22 and the seat 11.

The spring 43 normally holds the valve 40 in position to prohibit flow through the registering ports of the gasket and the disc 32; but if the pressure within the vehicle cooling system should drop substantially below atmospheric pressure, the valve 40 will be depressed, against the tendency of the spring 43, to permit air flow past said valve 40 into the system. If pressure within the system should rise to a value substantially above atmospheric pressure, the entire valve assembly and the ring 26 will be lifted, against the tendency of the spring 30, to permit steam to escape between the seat 11 and the gasket 36. The sealing member 20, of course, holds that steam against discharge past the cap member 15, and forces it to flow through the overflow pipe 14.

The ease of assembly of our cap is an important feature thereof. The cap member 15 is laid on a bench or in a holder in inverted position. The sealing member 20 is dropped into place, being guided by the boss 19, and the spring 30 is then

set in position upon said sealing member. The elongated member 22 is threaded through the opening defined by the flange 27 of the spring seat 26, and said spring seat centered on the end of the spring 30 remote from the sealing member 20. Preferably, the cylindrical wall of the spring seat 26 is so dimensioned as to have a frictional engagement with the inner surfaces of the first two turns of the spring 30.

The rivet 24 has been previously headed over against the outer surface of the cap 15, and its stem is projecting through the opening 21. Now the spring 30 is compressed to bring the flange 23 into engagement with the inner surface of the boss 19, whereby the stem of the rivet 24 is projected through the opening defined by the flange 23; and said stem is headed over to secure the member 22 to the cap member 15.

The parts of the valve assembly 31 having been previously assembled, the flange 34 is now slipped onto the flange 29 and crimped over to complete the assembly of the cap.

Of primary importance to the invention is the particular construction of the hollow element 22. As shown, it comprises two fingers 44 and 45 depending, in substantial parallelism with the axis of the perforation 46, from the flange 23, spaced apart by openings 47 and 48, and terminating in the outturned projections which define the flange 25. Each of fingers 44 and 45 is curved about said axis, so that said fingers define a cylinder, interrupted by the openings 47 and 48 which extend through the flange 25 and into a region near the flange 23.

This unit 22, as shown, may be very inexpensively punched and drawn from a single, rectangular strip of sheet metal. After punching the central perforation 46, the ends and sides of the blank are bent out of the original plane, drawing the portion 49 to define the solid cylindrical surface above the openings 47 and 48, and curving the bodies of the fingers 44 and 45. The lateral edges of said fingers do not meet, whereby said openings 47 and 48 are defined; and the terminal portions of the fingers are turned outwardly to define the flange 25.

We claim as our invention:

1. In a pressure-vacuum relief closure cap, a cap member formed for retaining association with a spout, a resilient sealing member loosely engaging the inner surface of said cap member, an elongated hollow element having an upper in-turned flange means and a lower outturned flange means, means cooperating with said in-turned flange means to secure said hollow element to the inner surface of said cap member, a ring slidably mounted on said hollow element and cooperable with the outturned flange of said hollow element to limit movement of said ring axially in one direction relative to said hollow element, said ring having an axial length substantially less than that of said hollow element, a coiled spring arranged to enclose said hollow element and confined between said ring and said sealing member to press said sealing member frictionally against the inner surface of said cap member, and a valve assembly including a pressure-relief valve and a vacuum-relief valve carried by said ring, a portion of said valve assembly projecting into the interior of said hollow element.

2. The cap of claim 1 in which said hollow element is a single piece of sheet metal whose periphery is interrupted, from said outturned

flange to a region near said inturned flange, by two openings substantially diametrically opposite each other.

3. In a sealing closure cap for vehicle radiators and the like, a cap member formed for retaining association with a spout, an elongated hollow element provided with radially-extending projections at its opposite ends, means cooperating with such projections at one end of said element to fix said element to the interior surface 10 of said cap member, a spring seat mounted on said element for reciprocation and rotation relative to the axis of said element, said spring seat having an axial length substantially less than that of said element and cooperating with such projections at the other end of said element to limit movement of said spring seat away from said cap member, spring means bearing on said spring seat and resiliently urging said spring seat toward cooperative engagement with said 20 last-named projections, and a valve assembly attached to said spring seat.

4. The cap of claim 3 in which said hollow ele-

ment comprises a single strip of stiff sheet material centrally perforated for the accommodation of said means and having a plurality of fingers projecting away from said cap member in substantial parallelism with the axis of its perforation, said fingers being spaced from each other peripherally of said axis and terminating in radial projections with which said spring seat cooperates.
